CLAIM

The ornamental design for a statue, as shown and described.

DESCRIPTION

FIG. 1 is a front view of a statue showing my new design; FIG. 2 is a rear view of the statue; FIG. 3 is a left side view of the statue; FIG. 4 is a right side view of the statue; FIG. 5 is a top view of the statue; FIG. 6 is a bottom view of the statue; and, FIG. 7 is a top front side perspective view of the statue. The broken lines in the drawings illustrate portions of the statue that form no part of the claimed design.

1 Claim, 7 Drawing Sheets
